UNITED STATES PATENT OFFICE.

HENRY M. WEAVER, OF MANSFIELD, OHIO.

LAVATORY.

No. 921,574.

Specification of Letters Patent.

Patented May 11, 1909.

Application filed March 9, 1907, Serial No. 361,584. Renewed October 15, 1908. Serial No. 457,915.

To all whom it may concern:

Be it known that I, HENRY M. WEAVER, a resident of Mansfield, in the county of Richland and State of Ohio, have invented certain new and useful Improvements in Lavatories, and do hereby declare the following to be a full, clear, and exact description of the invention, such as will enable others skilled in the art to which it appertains to make and use the same.

My invention relates to improvements in lavatories, adaptable alike to bath tubs as well as basins, but are shown in the drawing as applied to a basin,—the object of the invention being to simplify the construction of lavatories and improve the sanitary results.

A further object is to so construct a lavatory that it can be easily kept clean and so as to minimize the space usually occupied by the water inlets and overflow outlets.

A further object is to utilize the same opening in the lavatory, for the inlet of water and for the overflow.

With these objects in view, the invention consists in certain novel features of construction and combinations and arrangements of parts as hereinafter set forth and pointed out in the claims.

In the accompanying drawings; Figure 1 is a sectional view of a basin showing the application of my improvements thereto; Fig. 2 is a detail view of the spout and attached devices. Fig. 3 is a sectional view on the line $x-x$ of Fig. 1. Fig. 4 is a view of a modification.

1 represents a basin having an outlet 2 in its bottom and provided with a waste duct 3, communicating in a manner hereinafter described, with the basin near the top of the latter and with an outlet 4 located under and in line with the outlet 2 of the basin.

The wall of the basin is provided near its upper end, with an opening 5 and over said opening, a hood 6 is disposed, said hood forming a passage for water and being preferably made integral with the wall of the basin. A water inlet chamber 7 is located against the outer wall 8 of the waste duct and provided with a spout 9 projecting through an opening 10 in said wall, said spout also extending across the waste duct and having its free end bent downwardly and terminating within the hood 6. The wall of the opening 10 is made with notches 11 for the passage of lugs 12 at diametrically oppo-

site sides of the spout 9, said lugs being adapted to lie against the wall of the waste duct (within the latter), when the spout and the chamber from which it projects are turned slightly after the lugs have been passed through the notches 11, as shown in Fig. 3. The wall of the chamber 7 is threaded externally as shown at 13, for the reception of a collar 14, said collar having a peripheral flange 15, between which and the wall of the waste duct, a packing or gasket 17 is disposed. From this construction and arrangement of parts, it will be seen that by screwing up the collar 14, when the lugs 12 are disposed as shown in Fig. 1 and in dotted lines in Fig. 2, the fixture will be securely clamped to the wall of the waste duct. The chamber 7 is adapted to have connected therewith, both the hot and the cold water pipes and the valves for these pipes will be controlled by means of suitable hand-operated devices located above the slab of the basin. These valves and their operating means do not form any part of my present invention and are not shown in the drawing.

It will be observed that there is considerable space within the hood 6 not occupied by the spout 9 and hence the overflow from the basin will have free exit through said hood to the waste duct 3. Thus the hood has a double purpose,—viz., as the hot and cold water inlet for the basin and also as the waste outlet for the basin. The hood protrudes but a short distance into the basin and thus the space within the latter for the accommodation of fixtures is reduced to a minimum; the appearance of the basin will be improved, and the combined inlet and outlet for water can be easily kept clean.

In the construction shown in Fig. 4, the spout is provided with a plate 18 having a nipple 19 for the reception of a water inlet connecting device 20. The plate 18 is also provided with lugs or ears 21 through which screws 22 pass for securing the device to the wall 8 of the lavatory and between said wall and the plate 8 a packing ring is disposed.

My improvements are simple in construction; are applicable to any form of lavatory, whether a basin or a bath tub,—and are effectual in the performance of the functions for which they are invented.

Various slight changes might be made in the details of construction of my invention without departing from the spirit thereof or limiting its scope and hence I do not wish to

limit myself to the precise details herein set forth.

Having fully described my invention what I claim as new and desire to secure by Letters-Patent, is:—

1. The combination with a lavatory having an opening in its wall, a hood within the lavatory over said opening, means terminating under said hood for discharging water into the lavatory, and an overflow duct communicating with said opening.

2. The combination with a lavatory having an opening in its wall, of a hood within the lavatory over said opening, means terminating under the hood for discharging water into the lavatory, and means for conducting overflow from the lavatory through said hood.

3. The combination with a lavatory having an opening in its wall, of a water spout projecting through said opening, a water chamber communicating with said spout, means for securing said spout and water chamber in place, a hood within the lavatory over the opening in the latter, said hood inclosing the outlet of the spout, and an overflow duct communicating with said opening.

4. The combination with a lavatory provided with an overflow duct, the walls of said duct having alined openings, of a water

chamber having an externally threaded wall, a collar to screw on said wall and clamp the outer wall of the overflow duct, a spout communicating with said chamber, extending through the alined openings of the overflow duct and entering the interior of the lavatory, and lugs on said spout engaging the inner face of the outer wall of the overflow duct.

5. The combination with a lavatory provided with an overflow duct communicating with the interior of the lavatory and having an opening in its outer wall, the wall of said opening having notches, of a water chamber having an externally threaded wall, a collar screwed on said threaded wall, a washer or gasket interposed between said collar and the outer wall of the overflow duct, a spout communicating with said chamber and adapted to discharge into the lavatory, and lugs on said spout to pass through the notches in the wall of the opening in the outer wall of the overflow duct and engage the inner face of said outer wall.

In testimony whereof, I have signed this specification in the presence of two subscribing witnesses.

HENRY M. WEAVER.
